Application August 8, 1945, Serial No. 609,692

9 Claims. (Cl. 178—44)

(Granted under the act of March 3, 1883, as
amended April 30, 1928; 370 O. G. 757)

1

This invention relates to a rotatable coupler for the transmission of alternating current between two transmission lines rotating with respect to one another, and is particularly directed to the capacitive type of such rotatable coupler.

Rotatable couplers which are used to couple one transmission line to a second transmission line which is connected to a rotating antenna commonly employ inductive coupling, which results in rather sharp tuning and considerable restriction on the width of the frequency band passed. The frequency band passed by a rotatable coupler employing capacitive coupling is markedly broader than that passed by a rotatable coupler of the inductive type.

Furthermore, a capacitive rotatable coupler may be constructed with a diameter relatively small or quite large, as is desired, whereas the diameter of the inductive type coupler is fixed within rather narrow limits by the frequency of the voltage to be passed, since the loop type coupler must not be more than about one-quarter wave length in circumference. The capacitive type coupler thus allows more flexibility in design than the inductive type.

It is accordingly one object of this invention to provide a rotatable coupler for coupling two transmission lines which will pass radio frequency energy over a relatively wide band of frequencies.

It is another object of the invention to provide such a rotatable coupler which is strong mechanically and of simple construction.

It is also an object of this invention to provide a capacitive rotatable coupler for coupling a transmission line to a rotating antenna, which coupler may have a large enough internal diameter that it may be positioned around an antenna mount of relatively large external diameter.

It is another object of this invention to provide a capacitive rotatable coupler whose transmission characteristics will not vary greatly with the relative rotation of the upper element with respect to the lower element of the coupler.

In the accompanying drawings:

Figure 1 is a diagrammatic representation of one embodiment of this invention, and

Figure 2 is a section view of an embodiment of this invention showing certain structural details thereof.

In the embodiment of this invention shown in Figure 1 concentric annular conducting plates 1 and 2, fixed with respect to each other, are similar in shape and dimensions to plates 3 and 4, which are also fixed with respect to each other. The distance between the first and second pairs

5 of plates is exaggerated in the drawing; the plates are in practice separated by only a small distance, for example, one-eighth of an inch. These four plates are positioned coaxially so that plates 1 and 2 rotate with respect to plates 3 and 4 about their common axis.

Adequate means of insulation and support of the plates can be developed for any set of requirements, as this invention permits of considerable flexibility in choice of the dimensions 10 of the plates. The following dimensions were employed in an embodiment such as is illustrated in Figure 1 which was designed to surround a rotating antenna mount having an external diameter of somewhat less than twelve inches: external diameter of rings 1 and 3—20 inches, internal diameter of rings 1 and 3—17 inches, external diameter of rings 2 and 4—16 inches, and internal diameter of rings 2 and 4—12 inches. This embodiment was used with good results to 15 pass a frequency band of about 10 per cent in the neighborhood of 200 mc./s.

In the embodiment of Figure 1 the capacitive rotatable coupler serves to couple unbalanced transmission line 5 with unbalanced transmission line 6. Transmission line 5 feeds line-balance converter 7, while transmission line 6 feeds line-balance converter 8.

From line-balance converter 7 three parallel wire transmission lines 11, 12 and 13 lead to plates 1 and 2. One wire of each of transmission lines 11, 12 and 13 is connected to plate 1 at feed points 120° apart from each other, while the other wire of each of these three transmission lines is connected to plate 2 at feed points having substantially the same radial positions as the three points of connection for plate 1. From line-balance converter 8 two parallel wire transmission lines 14 and 15 lead to plates 3 and 4. One wire of each of transmission lines 14 and 15 is connected to plate 3 at feed points 180° apart from each other, while the other wire of each of these two transmission lines is connected to plate 4 at feed points having substantially the same radial positions as the points of connection for plate 3. The feed points for any one of transmission lines 11 through 15 will hereinafter be referred to as pairs of feed points for the respective plates.

In the operation of this invention, alternating voltages may be applied on either side of the rotatable coupler and alternating current will be transmitted through the coupler. If an alternating voltage is applied to one wire of each of parallel wire transmission lines 11, 12 and 13, for example, with an alternating voltage of in-

verse phase applied to the other wire of each of these three transmission lines, these alternating voltages will appear on capacitor plates 1 and 2. Alternating voltages of exactly the opposite phase will be induced on the other capacitor plates 3 and 4, respectively, and will thus be impressed on transmission lines 14 and 15, causing alternating current to flow therein. Since the capacitor comprised of plates 1 and 3 and the capacitor comprised of plates 2 and 4 are of large capacitance, the capacitive reactance presented by this rotatable coupler to the transmission of alternating current is very small.

It will be seen that as plates 1 and 2 rotate with respect to plates 3 and 4, at no time is more than one pair of feed points for plates 1 and 2 aligned radially with a pair of feed points for plates 3 and 4. If at any instant one pair of feed points for plates 1 and 2, say at the termination of transmission line 11, has the same bearing as a pair of feed points for plates 3 and 4, say at the termination of transmission line 14, then at that instant the pairs of feed points for plates 1 and 2 at the termination of transmission lines 12 and 13 will each be 60° away from the pair of feed points for plates 3 and 4 at the termination of transmission line 15.

Because of this fact, the rotatable coupler of this invention presents to alternating current of a given frequency an impedance which remains reasonably flat, without any sharp peaks, as plates 1 and 2 are rotated through 360° with respect to plates 3 and 4.

The number of parallel wire transmission lines feeding the upper and lower pairs of plates may be varied as desired and the flat impedance with relative rotation of the two halves of the coupler will be retained, if the number of transmission lines feeding one pair of plates is neither a factor nor an integral multiple of the number of transmission lines feeding the other pair of plates. For, if this numerical relationship is maintained, then at no time will more than one pair of feed points for plates 1 and 2 be aligned radially with a pair of feed points for plates 3 and 4.

Figure 2 shows in section how plates 1 and 2 may be rotatably mounted with respect to plates 3 and 4. Shaft 20 may be, for example, an antenna pedestal supporting rotatably thereon shaft 21, journaled in bearing 22 of shaft 20. Attached to shaft 20 is an annular plate 23, and attached to shaft 21 is annular plate 24. Plate 1 is attached to plate 24 by a number of insulators 25, and plate 2 is also attached to plate 24 by a number of insulators 26. In the same way plates 3 and 4 are attached to plate 23 through insulators 27 and 28, respectively. It will be seen that plates 1 and 2 will rotate with respect to plates 3 and 4 as shaft 21, supporting an antenna, for example, rotates with respect to shaft 20.

It will be understood that because of the width of the annular plates 1 through 4 slight lateral displacements of any of those plates will not result in undue variations in the transmission characteristics of this rotatable coupler as transmission line 5 rotates with respect to transmission line 6.

In case this invention is to be employed in coupling two balanced transmission lines, the embodiment of Figure 1 may of course be modified by elimination of line-balance converters 7 and 8. The operation of such a rotatable coupler would be in all other respects similar to that of the embodiment of Figure 1.

It will be understood that the embodiment

shown and described is exemplary only, and that the scope of the invention will be determined with reference to the appended claims.

The invention described herein may be manufactured and used by or for the Government of the United States of America for governmental purposes without payment of any royalties thereon or therefor.

What is claimed is:

10. A rotatable coupler for the transmission of alternating electric current between two balanced transmission lines rotating with respect to each other comprising two coaxial annular conducting plates fixed with respect to each other, a number of "m" of parallel wire transmission lines feeding said two plates, one wire of each of said "m" transmission lines being connected to one of said plates at points spaced substantially

20 $\frac{360}{m}$

degrees from each other and the other wire of each of said "m" transmission lines being connected to the other of said plates at points having substantially the same radial positions as the corresponding points of connection on said one plate, said "m" parallel wire transmission lines being fed in parallel by one of said two balanced transmission lines, third and fourth coaxial annular conducting plates fixed with respect to each other and of substantially the same lateral dimensions as the first two plates, a number "n" of parallel wire transmission lines feeding said third and fourth plates in the same way as the first two plates at connection points spaced

30 $\frac{360}{n}$

40 degrees from each other, the number "n" being any number neither a factor nor an integral multiple of said number "m," said "n" parallel wire transmission lines being fed in parallel by the other of said two balanced transmission lines, the second pair of plates being positioned coaxially with the first pair and separated by a small distance from said first pair, and means for rotatably mounting one of said pairs of plates with respect to the other of said pairs of plates.

50 2. A rotatable coupler for the transmission of alternating electric current between two unbalanced transmission lines rotating with respect to each other comprising two coaxial annular conducting plates fixed with respect to each other, a number "m" of parallel wire transmission lines feeding said two plates, one wire of each of said "m" transmission lines being connected to one of said plates at points spaced substantially

60 $\frac{360}{m}$

degrees from each other and the other wire of each of said "m" transmission lines being connected to the other of said plates at points having substantially the same radial positions as the corresponding points of connection on said one plate, a line-balance converter feeding said "m" transmission lines in parallel and being fed by one of said two unbalanced transmission lines, third and fourth coaxial annular conducting plates fixed with respect to each other and of substantially the same lateral dimensions as the first two plates, a number "n" of parallel wire transmission lines feeding said third and fourth

plates in the same way as the first two plates at connection points spaced.

360

n

degrees from each other, the number " n " being any number neither a factor nor an integral multiple of said number " m ," second line-balance converter feeding said " n " parallel wire transmission lines in parallel and being fed by the other of said two unbalanced transmission lines, the second pair of plates being positioned coaxially with the first pair and separated by a small distance from said first pair, and means for rotatably mounting one of said pairs of plates with respect to the other of said pairs of plates.

3. A rotatable coupler for the transmission of alternating electric current between two balanced transmission lines rotating with respect to each other comprising two coplanar coaxial annular conducting plates fixed with respect to each other, a number " m " of parallel wire transmission lines feeding said two plates, one wire of each of said " m " transmission lines being connected to one of said plates at points spaced substantially

360

m

degrees from each other and the other wire of each of said " m " transmission lines being connected to the other of said plates at points having substantially the same radial positions as the corresponding points of connection on said one plate, said " m " parallel wire transmission lines being fed in parallel by one of said two balanced transmission lines, third and fourth coplanar coaxial annular conducting plates fixed with respect to each other and of substantially the same lateral dimensions as the first two plates, a number " n " of parallel wire transmission lines feeding said third and fourth plates in the same way as the first two plates at connection points spaced

360

n

degrees from each other, the number " n " being any number neither a factor nor an integral multiple of said number " m ," said " n " parallel wire transmission lines being fed in parallel by the other of said two balanced transmission lines, the second pair of plates being positioned coaxially with the first pair and separated by a small distance from said first pair, and means for rotatably mounting one of said pairs of plates with respect to the other of said pairs of plates.

4. A rotatable coupler for the transmission of alternating electric current between two unbalanced transmission lines rotating with respect to each other comprising two coplanar coaxial annular conducting plates fixed with respect to each other, a number " m " of parallel wire transmission lines feeding said two plates, one wire of each of said " m " transmission lines being connected to one of said plates at points spaced substantially

360

m

degrees from each other and the other wire of each of said " m " transmission lines being connected to the other of said plates at points having substantially the same radial positions as the corresponding points of connection on said one plate, a line-balance converter feeding said " m " transmission lines in parallel and being fed by

one of said two unbalanced transmission lines, third and fourth coplanar coaxial annular conducting plates fixed with respect to each other and of substantially the same lateral dimensions as the first two plates, a number " n " of parallel wire transmission lines feeding said third and fourth plates in the same way as the first two plates at connection points spaced

360

n

degrees from each other, the number " n " being any number neither a factor nor an integral multiple of said number " m ," second line-balance converter feeding said " n " parallel wire transmission line in parallel and being fed by the other of said two unbalanced transmission lines, the second pair of plates being positioned coaxially with the first pair and separated by a small distance from said first pair, and means for rotatably mounting one of said pairs of plates with respect to the other of said pairs of plates.

5. A rotatable coupler for the transmission of alternating electric current between two transmission line systems rotatable with respect to each other comprising " m " transmission lines fed in parallel by one of said two transmission line systems, means for displacing each of the " m " parallel connected transmission lines with respect to each other so that the commonly fed wires of said transmission lines are located at different points along the circumference of the same circle, " n " transmission lines in parallel circuit relation connected to the other of said two transmission line systems, means for displacing each of the " n " parallel connected transmission lines from each other so that the wires which are commonly connected are located at different points along the circumference of the same circle which has substantially the same diameter as and which is coaxial with, and is in close proximity to, one of the circles about which the commonly connected wires of the " m " transmission lines are connected, each of said displacing means comprising conductive plates to which the " m " parallel connected transmission lines and the " n " parallel connected transmission lines are respectively connected.

6. A rotatable coupler for the transmission of alternating electric current between two transmission line systems rotatable with respect to each other comprising " m " transmission lines fed in parallel by one of said two transmission line systems, means for displacing each of the " m " parallel connected transmission lines with respect to each other so that the commonly fed wires of said transmission lines are located along the circumference of the same circle, " n " transmission lines in parallel circuit relation connected to the other of said two transmission line systems, means for displacing each of the " n " parallel connected transmission lines from each other so that the wires which are commonly connected are located along the circumference of the same circle which has substantially the same diameter as and which is co-axial with, and is in close proximity to, one of the circles about which the commonly connected wires of the " m " transmission lines are located, each of said displacing means comprising conductive plates to which the " m " parallel connected transmission lines and the " n " parallel connected transmission lines are respectively coupled, the number of " n " is neither a factor nor an integral multiple of said number " m ."

7. A rotatable coupler for the transmission of alternating current between a first two wire transmission line rotatable with respect to a second two wire transmission line, comprising a first pair of co-axially disposed annular conducting plates, a plurality of connections between each conductor of said first line and a different one of said conducting plates at various angular points around the circumference of said plates, a second pair of co-axially disposed annular conducting plates of similar dimension located in close proximity to the first pair and rotatable with respect thereto, and a connection between each conductor of the second line and the respective plates of the second pair at various angular positions around the circumference thereof, the connections to the second pair of plates having a different angular relationship than those to the first pair of plates.

8. A rotatable coupler for the transmission of alternating current between a first transmission line and a second transmission line which is rotatable relative to said first transmission line comprising a first set of co-axially disposed annular conducting plates, one for each conductor of the first line, a plurality of connections between each conductor of the first line and a different one of said conducting plates at various angular points around the circumference of the plates, a second set of co-axially disposed annular conducting plates, of similar dimension and located in close proximity to the said first set of plates, and rotatable with respect thereto, one for each conductor of the second line, a connection between each conductor of the second line and a respective conducting plate of said second set of plates at various angular points around the circumference of the plates the connections to said second set of plates having a different angular relationship than those to said first set of plates.

9. In a rotary coupler system wherein energy is coupled between two transmission line systems through a first and second set of respectively

5 capacitive plates where one of the plates of each set are simultaneously rotatable with respect to the associated plate of each set, and where the impedance variations between the said sets of plates varies appreciably with rotation of the rotatable plates thereof, the improvement comprising "m" transmission lines connected in parallel to one of said two transmission line systems, means connecting each set of commonly connected conductors of said transmission lines respectively to a different rotatable plate of said sets of plates, the commonly connected conductors connecting to the associated plate at different points thereon surrounding the axis of rotation thereof, "n" transmission lines connected in parallel to the other one of said transmission line systems, means connecting the sets of commonly connected conductors of said latter transmission lines respectively to a different one of the other plates of said respective sets of plates, the commonly connected conductors connecting to the associated plate at different points about the axis of rotation of the associated rotatable plate, the number "n" being neither a factor nor an integer of said number "m".
